Patented Nov. 9, 1976

242,258

HOLDER FOR A HAND HELD DATA READER OR THE LIKE

Bruce M. McPherson, Ithaca, N.Y., assignor to
NCR Corporation

Filed Oct. 24, 1975, Ser. No. 625,408

Term of patent 14 years

Int. Cl. D16—06; D19—02
U.S. Cl. D26—5 C

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a front perspective view of a holder for a hand held data reader or the like showing my new design;

FIG. 2 is a left side elevational view thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a rear perspective view of a modified form of the holder for a hand held data reader or the like in FIG. 1;

FIG. 8 is a front perspective view of the modified form shown in FIG. 7;

FIG. 9 is a left side elevational view of the modified form thereof;

FIG. 10 is a top plan view of the modified form thereof;

FIG. 11 is a rear elevational view of the modified form thereof.

FIG. 12 is a front elevational view of the modified form thereof; and

The undisclosed bottom plan view of the FIG. 7 embodiment is substantially the same in appearance as the bottom view shown in FIG. 6.

I claim:

The ornamental design for a holder for a hand held data reader or the like, as shown and described.
